BLOWPIPE LIGHTER

Herbert W. Cowin, Westfield, and Wilgot J. Jacobsson, Elizabeth, N. J., assignors, by mesne assignments, to Union Carbide and Carbon Corporation, a corporation of New York

Application August 9, 1934, Serial No. 739,092

17 Claims. (Cl. 158—27.4)

This invention relates to a fluid fuel burner and more particularly to an improved pilot light for such a burner which will consume a minimum amount of fuel and yet be always ready for lighting the burner.

It is desirable to have available a pilot light for lighting burners when they become extinguished, and it is necessary that such pilot lights remain lighted continuously during intermittent use of the burner. Economy in the amount of fuel consumed by the pilot light is frequently an important factor, and when this requirement exists it is necessary to maintain the continuously burning pilot light with as small a flame as possible. The danger always exists, however, that the small flame may be extinguished by drafts, and it therefore becomes necessary to shield the pilot flame against such drafts. On the other hand, with the use of some fluid fuels, such as acetylene, restriction by a shield of the air coming to the pilot burner is a serious handicap since sufficient air must be supplied to the pilot light burner when the flame is enlarged for lighting the main burner. It is necessary therefore, to shield the flame and at the same time to make sure that sufficient air will reach the pilot light burner under all conditions of operation.

From the foregoing discussion it will be evident that the invention is particularly useful in connection with a lighter for blowpipes such as those employed in welding, cutting or deseaming metals. In the use of such blowpipes one operation after another is performed; but between successive operations it is highly desirable temporarily to shut off the welding or heating gases for the sake of fuel economy.

One object of this invention, therefore, is to provide means for shielding the pilot flame from drafts which may extinguish it, thereby permitting a minimum gas consumption when the main burner is not in use, and at the same time to provide ample air for the enlarged or extended flame required for lighting the main burner. Another object is the provision of metering means in the pilot burner construction in order to prevent undue fuel consumption. A further object is the screening of the fuel coming to the metering means and the pilot light nozzle. Still a further object is the screening of air coming to the pilot light nozzle in order to prevent clogging of the air passages in this nozzle by scale or other foreign matter. The above, and other objects and the novel features of the invention will be come apparent from the following description

and the accompanying drawing which illustrates one embodiment of the invention, and in which:

Fig. 1 is a broken longitudinal elevation of a blowpipe embodying the invention;

Fig. 2 is a partial longitudinal mid-section illustrating one form of the invention;

Fig. 3 is a partial longitudinal mid-section corresponding to Fig. 2 illustrating a variant form of the invention; and

Fig. 4 is a fragmentary cross-section showing certain related parts of the blowpipe construction.

The embodiment illustrated in the drawing shows the invention as applied to an oxy-acetylene blowpipe, but it will be realized that the invention is applicable to other forms of fluid fuel burners.

In the drawing there is shown a blowpipe comprising a handle 10, having a valve body section 11 at its rear end, together with a lever 12 for controlling the heating flame, and a valve knob 13 for controlling the cutting oxygen. A stem section 14 connects the handle 10 with a head 15 to which is attached a tip 16 in the usual manner.

It is preferred to place the pilot burner close to the underside of the head 15 at some distance from the end of the nozzle in a position to protect the burner from knocks, heat from cutting and slag. Thus, a bracket 17 is carried by the stem 14 in any convenient manner and is here shown as being clamped by means of bolts 18 to one of the conduits 19 comprising the stem 14. The bracket 17 has a bore 20 through it; and a fuel conduit 21 communicates with the bore 20 in the bracket, for instance, by having the end of the conduit inserted in an enlarged section 22 of the bore and soldered therein. The fuel conduit 21 may be connected with any source of fluid fuel and in an acetylene blowpipe such as that here illustrated, is preferably connected with the source of acetylene in the valve body.

The bracket 17 has a projection 23 thereon extending generally toward the far end of the tip 16 of the blowpipe. The bore 20 in the bracket extends through and to the end of this projection, which is both externally and internally threaded substantially concentrically with the bore. Thus, acetylene coming to the bracket through the fuel conduit 21 may pass through the bore 20 in the bracket and out of the threaded end of the projection 23 thereof. A pilot light nozzle 24 externally threaded at one end may be screwed into the internal thread at the end of the projection 23 of the bracket 17, and a substantially axial fuel passage 25 in the nozzle will

thus be brought into communication with the end of the bore 20 in the bracket from which it will receive the acetylene passing through the bore. There is also provided in the nozzle 24 one or more air passages 26 disposed at an angle to the fuel passages with an external opening or external openings in the surface of the nozzle. The axial fuel passage 25 having a constricted throat 27 through which fuel coming to the nozzle must pass immediately before passing the inner ends of the air passages 26, an aspirating action will be exerted by the fuel upon any air in the air passages 26 which will be mixed with the fuel and projected from the end of the nozzle 24.

15 Normally, acetylene coming to the pilot light nozzle 24 will be restricted to a minimum quantity to keep the light burning. One means for controlling the access of acetylene to the pilot light nozzle is illustrated by the construction shown in Fig. 4. In this arrangement acetylene enters the passages in a valve block 28 through a conduit 29 and passes through a bore 30 to a duct 31 at the end of which a valve 32 is positioned to control the rate of flow of the acetylene.

20 A valve stem 33 connects the valve 32 to a threaded portion 34 which turns in corresponding threads in the valve block 28. The position of the valve 32 is adjusted by turning a head 35 having a kerf 36 therein, the head being fast to the threaded portion 34, the head 35 having therebeneath a washer of such resiliency that it will maintain contact between the block 28 and the head 35 for varying positions of the valve 32. Acetylene passing the valve 32 enters a valve chamber 37 and passes thence through a duct 38 to the fuel conduit 21. Thus, by turning the head 35 in one direction the amount of acetylene reaching the pilot light nozzle 24 will be lessened, whereas turning the head 35 in the other direction will increase the amount of acetylene reaching the pilot light nozzle. It is desirable to adjust the head 35 in such a manner as to provide a minimum amount of acetylene to the nozzle 24 and a minimum length of flame at its end.

25 A second valve is provided in the valve block 28 for effecting a rush of fuel to the pilot light nozzle 24 and thus extending the flame to such a length that it will project in front of the blowpipe nozzle 16 to light the gases issuing therefrom. This second valve arrangement comprises a hollow nut 39 having a valve seat 40 at its lower end and being adapted to screw into a threaded cavity 41 in the valve block 28. A central passage 42 through the hollow nut 39 connects with the duct 38 by means of a plurality of radial passages 43 extending therefrom to an annular space 44 formed between a recess in the hollow nut 39 and the valve block 28. The annular space 44 opens into the duct 38. A valve 45, carried by a valve stem 46 which is threaded at the end thereof opposite the valve 45 and screwed into an annular bushing 47 in a button 48, seats upon the valve seat 40, thereby normally closing the central passage 42 against access of fuel from the bore 30. A helical spring 49 in the hollow nut 39 bears upon the bushing 47 and tends normally to maintain the valve 45 in closed position.

30 When it is desired to use the pilot flame to light the gases issuing from the tip 16, the button 48 is pressed inwardly thereby opening the valve 45 and permitting an inrush of fuel gas which passes into the central passage 42 through the radial passages 43 to the annular space 44 and through the duct 38 to the fuel conduit 21. The sudden rush of fuel gas passes through the constricted

throat 27 and out through the axial fuel passage 25 with great velocity. The jet of flame is thus elongated by many times its original length, and, because of the rate at which it passes through the constricted throat 27, aspirates a large quantity of air which passes through the air passages 26 at an accelerated rate.

35 As best illustrated in Fig. 1, the pilot light control means is preferably located in the front handle bushing in such a position that the button 48 may be easily operated by pressure from the thumb of the hand holding the blowpipe.

40 In order to protect the normally small flame at the end of the nozzle 24 there is provided a shield 50, here illustrated as a hollow cylinder. One end of the shield 50 is internally threaded and is of such diameter that it may be screwed upon the externally threaded end of the projection 23 on the bracket 17. When the pilot light is used for lighting the gases issuing from the nozzle 16 and the rush of fuel gas is projected from the nozzle 24, it is necessary to supply quickly to the nozzle a greatly increased volume of air. This is especially the case where acetylene is used and a cloud of smoke will be formed unless sufficient air is present. Accordingly, a hole 51 is made in the shield 50 opposite the external opening of each air passage 26. Movement of air through the holes 51 will not tend to extinguish the flame at the end of the nozzle 24 because of the position of the holes in the shield; which serves to protect the flame at the end of the nozzle 24 in the desired manner. However, when the pressure in the air passages 26 is reduced the holes 51 provide means for access of an ample supply of air to the passages 26.

45 In order further to restrict the quantity of fluid fuel consumed by the pilot light when not in use a metering orifice may be provided between the supply of fluid fuel and the pilot light nozzle 24. One means of providing such a nozzle is to insert between the bracket 17 and the pilot light nozzle 24, a nipple wherein a metering orifice is formed, and such a construction is illustrated in Fig. 3 of the drawing. As shown in Fig. 3, a nipple 52, having a bore therein internally threaded at one end, is screwed upon the external thread of the bracket 17. The nipple 52 has a metering orifice 53 therein in continuation of the bore and is internally and externally threaded at one end like the projection 23. The pilot light nozzle 24 is screwed into the internal thread in the outer end of the nipple 52, and a shield 50' is screwed upon the external thread at the outer end of the nipple protecting the pilot light nozzle 24 as previously described. The resistance provided by the metering orifice 53 limits the volume of fluid fuel reaching the pilot light nozzle and requires an appreciable pressure within the bore of the nipple to cause passage of any considerable quantity of fuel through the nozzle.

50 It has been found that impurities are frequently carried by the fluid fuel. These impurities may be solids or even globules of liquid, and if allowed to reach the metering orifice or the constricted throat 27 in the pilot light nozzle will tend to clog its passages and prevent proper operation of the apparatus. Accordingly, one or more screens may be inserted in the bore of the nipple 52, and as here shown two screens 54 and 55 are so inserted, the screens themselves being conical in shape and having their apices pointing in the direction of fuel travel. The base edges of the screens are flared outwardly in the form of an

nular flanges and are held in place between an interior annular shoulder in the bore of the nipple and an externally threaded bushing 56 screwed into the internal threading in the nipple 52. The screens 54 and 55 have different conical altitudes thereby providing a space between them so that the fluid fuel is twice screened before reaching the metering orifice 53. Clearly, a single screen or more than two screens may be employed under 10 conditions permitting or requiring such screening.

It is even more likely that extraneous solids may be drawn into the pilot light nozzle 24 through the holes 51 in the shield 50 than that such solids may be carried in the fluid fuel. Accordingly, a screen is provided covering each hole in the shield. One form of screen for this purpose is indicated in Fig. 3, wherein a circular screen 57, of different diameters along its axial extent, is firmly held between an annular shoulder 58 in the shield 50 and the outer surface of the pilot light nozzle 24. The edge of the screen 57 adjacent the end of the nipple 52 may either rest upon the annular face of the nipple between the external and internal threads or may be otherwise attached at this point. Thus, air passing through the holes 51 in the shield 51 will be properly screened before entering the air passages 26 in the pilot light nozzle 24.

The examples here described and illustrated are presented merely to indicate how the invention may be applied. Other forms of the invention differing in detail but not in principle from that here described will, of course, suggest themselves to those skilled in this art.

We claim:

1. In a blowpipe, a pilot light nozzle having therein a substantially axial fuel gas passage and an air inlet passage at an angle to the fuel gas passage with an external opening in the surface of said nozzle, means for supplying said passage with a minimum quantity of gas, means for supplying said passage at will with an increased quantity of gas, and a shield for said nozzle, said shield having a hole therein adjacent the external opening of the air inlet passage in said nozzle, the hole in said shield serving to permit additional air easily to reach said air inlet passage upon increase of gas supply.

2. In a blowpipe, a pilot light nozzle having therein a substantially axial constricted fuel gas passage and an air inlet passage at an angle to the fuel gas passage with an external opening in the surface of said nozzle, a fuel gas supply conduit connected with the fuel gas passage in said nozzle, means for supplying said conduit with a minimum quantity of gas, means for supplying said conduit at will with an increased quantity of gas, and a conical screen having its apex pointing in the direction of fuel gas travel disposed in said conduit and serving to protect the constricted fuel gas passage in said nozzle from becoming clogged.

3. In a blowpipe, a pilot light nozzle having therein a substantially axial constricted fuel gas passage and an air inlet passage at an angle to the fuel gas passage with an external opening in the surface of said nozzle, a fuel gas supply conduit connected with the fuel gas passage, means for supplying said conduit with a minimum quantity of gas, means for supplying said conduit at will with an increased quantity of gas, and a pair of conical screens having their apices pointing in the direction of fuel gas travel disposed in said conduit, said screens having different conical alti-

tudes, said screens serving to protect the constricted fuel gas passage in said nozzle from becoming clogged.

4. In a fluid fuel burner, a pilot light nozzle having therein a substantially axial fuel passage and an air inlet passage at an angle to the fuel passage with an external opening in the surface of said nozzle, a nipple having a fuel metering orifice therein connected to said nozzle and opening into the fuel passage therein, and a conical screen having its apex pointing in the direction of fuel travel disposed in said nipple on the pressure side of the fuel metering orifice therein to prevent clogging of the orifice by particles in the fuel gas.

5. In a blowpipe, a pilot light nozzle having therein a substantially axial fuel gas passage and an air inlet passage at an angle to the fuel passage with an external opening in the surface of said nozzle, means for supplying said passage with a minimum quantity of gas, means for supplying said passage at will with an increased quantity of gas, a shield for said nozzle, said shield having a hole therein adjacent the external opening of the air passage in said nozzle, and a screen covering the hole in said shield, the hole in said shield serving to permit additional air easily to reach said air inlet passage upon increase of gas supply.

6. In a fluid fuel burner, a pilot light nozzle having therein a substantially axial fuel passage and an air inlet passage at an angle to the fuel passage with an external opening in the surface of said nozzle, a fuel conduit connected with the fuel passage in said nozzle, and a conical screen having its apex pointing in the direction of fuel travel disposed in said conduit, in combination with a shield for said nozzle, said shield having a hole therein opposite the external opening of the air inlet passage in said nozzle, and a screen covering the hole in said shield.

7. In a fluid fuel burner, a pilot light nozzle having therein a substantially axial fuel passage and an air inlet passage at an angle to the fuel passage with an external opening in the surface of said nozzle, a nipple having a fuel metering orifice therein connected to said nozzle and opening into the fuel passage therein, and a conical screen having its apex pointing in the direction of fuel travel disposed in said nipple, in combination with a shield for said nozzle, said shield having a hole therein opposite the external opening of the air passage in said nozzle, and a screen covering the hole in said shield.

8. In a blowpipe, a bracket attached to the forward part of the blowpipe, a pilot light nozzle carried by said bracket, said nozzle having therein a substantially axial fuel passage and an air inlet passage at an angle to the fuel passage with an external opening in the surface of said nozzle, a shield for said nozzle independently carried by said bracket, said shield having a hole therein adjacent the external opening of the air inlet passage in said nozzle, a bore in said bracket communicating with the fuel passage in said nozzle, and a fuel conduit communicating with the bore in said bracket.

9. In a blowpipe, a bracket attached to the forward part of the blowpipe, a pilot light nozzle carried by said bracket, said nozzle having therein a substantially axial fuel passage and an air inlet passage at an angle to the fuel passage with an external opening in the surface of said nozzle, a shield for said nozzle independently carried by said bracket, said shield having a hole

therein opposite the external opening of the air passage in said nozzle, said bracket having a bore therein communicating with the fuel passage in said nozzle, a fuel conduit communicating with the bore in said bracket, and a screen covering the hole in said shield.

10. In a blowpipe, a bracket attached to the forward part of the blowpipe, a nipple attached to said bracket at one end, a pilot light nozzle attached to said nipple at the other end, said nozzle having therein a substantially axial fuel passage and an air inlet passage at an angle to the fuel passage with an external opening in the surface of said nozzle, a shield for said nozzle independently carried by said nipple, said shield having a hole therein opposite the external opening of the air inlet passage in said nozzle, a screen covering the hole in said shield and a conical screen having its apex pointing in the direction of fuel travel disposed in the bore of said nipple.

11. In a blowpipe, a bracket attached to the forward part of the blowpipe, said bracket having a bore therethrough; a fuel conduit connected to said bracket at one end of the bore therethrough; an external thread on said bracket substantially concentric with the other end of the bore; a nipple having a bore internally threaded at one end adapted to screw upon the external thread on said bracket, said nipple also having a metering orifice therein in continuation of the bore and being internally and externally threaded at its other end; a pilot light nozzle externally threaded at one end for screwing into said nipple, said nozzle having therein a substantially axial fuel passage and an air inlet passage at an angle to the fuel passage with an external opening in the surface of said nozzle; and a shield for said nozzle having an internal thread therein screwed upon the external thread of said nipple, said shield having a hole therein opposite the external opening of the air inlet passage in said nozzle.

12. In a blowpipe, a bracket attached to the forward part of the blowpipe, said bracket having a bore therethrough; a fuel conduit connected to said bracket at one end of the bore therethrough; an external thread on said bracket substantially concentric with the other end of the bore; a nipple having a bore internally threaded at one end adapted to screw upon the external thread on said bracket, said nipple also having a metering orifice therein in continuation of the bore, and being internally and externally threaded at its other end; a pilot light nozzle externally threaded at one end for screwing into said nipple, said nozzle having therein a substantially axial fuel passage and an air inlet passage at an angle to the fuel passage with an external opening in the surface of said nozzle; and a shield for said nozzle having an internal thread therein screwed upon the external thread of said nipple, said shield having a hole therein opposite the external opening of the air inlet passage in said nozzle; in combination with a conical screen having its apex pointing in the direction of fuel travel disposed in the bore of said nipple.

13. In a blowpipe, a bracket attached to the forward part of the blowpipe, said bracket having a bore therethrough; a fuel conduit connected to said bracket at one end of the bore therethrough; an external thread on said bracket substantially concentric with the other end of the bore; a nipple having a bore internally threaded at one end adapted to screw upon the external thread on said bracket, said nipple also having

a metering orifice therein in continuation of the bore and being internally and externally threaded at its other end; a pilot light nozzle externally threaded at one end for screwing into said nipple, said nozzle having therein a substantially axial fuel passage and an air inlet passage at an angle to the fuel passage with an external opening in the surface of said nozzle; and a shield for said nozzle having an internal thread therein screwed upon the external thread of said nipple, said shield having a hole therein opposite the external opening of the air passage in said nozzle; in combination with a pair of conical screens having their apices pointing in the direction of fuel travel disposed in the bore of said nipple, said screens having different conical altitudes.

14. In a blowpipe, a bracket attached to the forward part of the blowpipe, said bracket having a bore therethrough; a fuel conduit connected to said bracket at one end of the bore therethrough; an external thread on said bracket substantially concentric with the other end of the bore; a nipple having a bore internally threaded at one end adapted to screw upon the external thread on said bracket, said nipple also having a metering orifice therein in continuation of the bore and being internally and externally threaded at its other end; a pilot light nozzle externally threaded at one end for screwing into said nipple, said nozzle having therein a substantially axial fuel passage and an air inlet passage at an angle to the fuel passage with an external opening in the surface of said nozzle; and a shield for said nozzle having an internal thread therein screwed upon the external thread of said nipple, said shield having a hole therein opposite the external opening of the air inlet passage in said nozzle; in combination with a conical screen having its apex pointing in the direction of fuel travel disposed in the bore of said nipple; and a screen covering the hole in said shield.

15. In a blowpipe, a bracket attached to the forward part of the blowpipe, said bracket having a bore therethrough; a fuel conduit connected to said bracket at one end of the bore therethrough; an external thread on said bracket substantially concentric with the other end of the bore; a nipple having a bore internally threaded at one end adapted to screw upon the external thread on said bracket, said nipple also having a metering orifice therein in continuation of the bore and being internally and externally threaded at its other end; a pilot light nozzle externally threaded at one end for screwing into said nipple, said nozzle having therein a substantially axial fuel passage and an air inlet passage at an angle to the fuel passage with an external opening in the surface of said nozzle; and a shield for said nozzle having an internal thread therein screwed upon the external thread of said nipple, said shield having a hole therein opposite the external opening of the air inlet passage in said nozzle; in combination with a pair of conical screens having their apices pointing in the direction of fuel travel disposed in the bore of said nipple, said screens having different conical altitudes; and a screen covering the hole in said shield, substantially as described.

16. A blowpipe comprising a handle; a tip; and a stem joining said handle and said tip, said stem comprising conduits for fuel gas and combustion supporting gas; a bracket having a bore therethrough carried by said stem; and a fuel conduit in said stem connected to one end of the bore in said bracket; in combination with a pilot

light nozzle connected to said bracket, said nozzle having therein a substantially axial fuel passage in continuation of the bore in said bracket and an air inlet passage at an angle to the fuel passage with an external opening in the surface of said nozzle; and a conical screen having its apex pointing in the direction of fuel travel screening the fuel going to the fuel passage.

17. A blowpipe comprising a handle; a tip; and a stem joining said handle and said tip, said stem comprising conduits for fuel gas and combustion supporting gas; a bracket having a bore therethrough carried by said stem; and a fuel conduit in said stem connected to one end of the bore in

said bracket; in combination with a pilot light nozzle connected to said bracket, said nozzle having therein a substantially axial fuel passage in continuation of the bore in said bracket and an air inlet passage at an angle to the fuel passage with an external opening in the surface of said nozzle; a conical screen having its apex pointing in the direction of fuel travel screening the fuel going to the fuel passage; a shield for said nozzle, said shield having a hole therein opposite the external opening of the air passage in said nozzle; and a screen covering the hole in said shield.
